UNITED STATES PATENT OFFICE

CHARLES L. KRUM AND HOWARD L. KRUM, OF CHICAGO, ILLINOIS, ASSIGNEES, BY
MESNE ASSIGNMENTS, TO TELETYPE CORPORATION, OF CHICAGO, ILLINOIS, A COR-
PORATION OF DELAWARE

PRINTING-TELEGRAPH APPARATUS

Application filed October 13, 1919, Serial No. 330,325. Renewed August 8, 1928.

The invention relates to printing telegraph apparatus and seeks to provide an improved construction which will operate accurately and at high speeds. More particularly the 5 present invention seeks to improve the construction set forth in our prior United States Letters Patent No. 1,232,045, dated July 3, 1917.

The invention consists in the features here- 10 inafter set forth, illustrated in the preferred form in the accompanying drawings, and more particularly pointed out in the appended claims.

Figure 1 is a front elevation with the top 15 plate of the machine shown in section and with parts of the frame or casing removed or broken away. Fig. 2 is a plan view with parts shown in section on the line 2—2 of Fig. 1. Fig. 3 is a vertical section on an 20 enlarged scale on the line 3—3 of Fig. 1. Fig. 3^a is a detail section on the line a—a of Fig. 2. Fig. 4 is a side elevation of the upper left-hand portion of the machine illustrating the line-feed mechanism. Fig. 4^a is a 25 detail view in vertical elevation of parts shown in Fig. 2. Fig. 5 is a vertical section on the line 5—5 of Fig. 2. Fig. 6 is a vertical section of the selector mechanism at the 30 right-hand side of the machine. Fig. 7 is a horizontal section on the line 7—7 of Fig. 6. Fig. 8 is a side elevation of the parts 35 shown in Figs. 6 and 7 with the base plate shown in section. Figs. 8^a and 8^b are detail sections on lines a—a and b—b, respectively, of Fig. 8. Figs. 9 and 10 are vertical sections on the lines 9—9 and 10—10 of Fig. 6. Figs. 10^a, 10^b, 10^c and 10^d are detail views 40 of the selector plates. Fig. 11 is a diagram of the operating circuits.

The machine frame comprises a cast metal base plate 10, a set of corner posts 11 fixed to and extending upwardly from the base plate and a top plate 12 is mounted on and preferably removably attached to the upper 45 ends of the corner posts. Preferably sheet metal plates (not shown) extend between the corner posts for enclosing and protecting the operating parts of the machine which are largely arranged between the base and top 50 plates of the frame.

The paper sheet printed upon passes over a horizontal transverse platen 13 mounted upon the top plate of the machine. The platen shaft 14 is journaled in two brackets 15 that are fixed to and project upwardly 55 from the top plate, the shaft being provided at its ends with the usual finger piece 16. The sheet is guided to and from the platen roll by plates 17, 18 and 19 which extend between the brackets 15. A cooperating feed 60 roller 20 is mounted upon the upper ends of a pair of pivoted arms 21 which are spring-pressed to hold the feed roller 20 in engagement with the platen roll. A paper scale 23 also extends between the upper ends of 65 the arms 21 and is provided with paper guide fingers 24 which extend upwardly and inwardly over the roll.

At its left-hand end, the platen shaft is provided with a ratchet wheel 25 which is 70 arranged to be engaged by a pawl 26. The pawl is pivoted upon the upper end of a line-space lever 27 and is spring-pressed toward the ratchet wheel. The lever is fixed to a short shaft 28 journaled in the adjacent 75 platen bracket 15 and this shaft is provided with a rearwardly projecting arm 29 (see Figs. 3 and 4) which is arranged to be engaged by a vertically movable actuating rod 30. The latter is fixed to the armature yoke 80 of the double spool solenoid magnet 31 which is mounted upon and depends from the top plate 12. A spring connected to the line-space lever holds it in normal position with its upper end in engagement with the lug 85 32 on the rear end of an adjusting lever 33. The latter is pivotally mounted on the platen shaft and has a finger piece at its forward end. A fixed stop pin 34 extends into an opening in the lever 33 and limits its extent 90 of movement and a spring 35 engages its rear end and holds it in either raised or lowered position, so that it will variably limit the backward movement of the line-space lever. The magnet 31 is adapted to be energized 95 by the transmission of a special signal and when energized operates the line-space lever and advances the platen. Preferably, as shown, the line-space lever is provided with a fixed stop lug 36 which engages the ratchet 100

and prevents overthrow. A spring-held jockey pawl 37 also engages the ratchet to hold the platen against accidental movement. By shifting the lever 33, the throw of the lever 27 can be adjusted to effect single or double line spacing, since the lever has a one-way engagement with its actuating rod 30. The platen and the line-feed mechanism, including the line-feed magnet 31, are mounted on the top plate 12 which, as stated, is preferably removable. For this purpose, the circuit of the magnet extends through two spring-pressed contact plungers 31^a (see Fig. 4^a) which are mounted on one of the rear corner posts and are arranged to engage suitable jacks or contacts carried by the top plate.

The type are arranged upon a carrier or type-wheel 38 in two rows, the characters in the upper row and the figures and punctuation marks in the lower row. As in the construction set forth in the prior patent referred to, the typewheel is mounted upon a spindle 39 which slides longitudinally through a hollow shaft 40. This shaft is journaled in a swinging arm 41 having a yoke 42 at its lower end which is connected by pivot screws to a pair of upwardly projecting lugs 43 on a carriage 44 (see Figs. 1, 2 and 3). The lower end of the shaft 40 is connected by a universal coupling 45 to the upper end of a short vertical shaft 46 which is journaled in the carriage 44. The front portion of the carriage is provided with two bearing lugs 47 which slidably engage a heavy horizontal track bar or guide 48 which extends between and is fixed at its ends to vertical right and left hand brackets 49 and 50, mounted upon the base plate. The track bar 48 and the bearing openings in the lugs 47 are preferably cylindrical and a rearwardly projecting lug on the carriage is provided with a roller 51 which engages a cylindrical guide rod or rail 52 which extends between the upper rear portions of the brackets 49 and 50. A keeper 53 fixed to a depending lug on the rear portion of the carriage extends beneath the guide rail, but normally just out of contact therewith, and serves to prevent any undue oscillation of the carriage about its main guide or track 48. The carriage and the typewheel carried thereby are thus movable horizontally to effect the letter-spacing.

The typewheel is rotated to bring the proper type opposite the printing point and the arm 41 and typewheel carried thereby are oscillated to effect the impression of the selected type upon the paper on the platen by two horizontal shafts 54 and 55 which extend between and are journaled at their ends in the brackets 49 and 50. These shafts are preferably square in section, as shown. The shaft 44 is connected to the rotating typewheel by a pair of intermeshing beveled pinions 56 and 57, one of which is fixed to the lower end of a short vertical shaft 46 and

the other of which is arranged to slide upon the shaft 54, but has a square opening through which the shaft extends and, therefore, rotates with the shaft. The carriage is provided with a depending lug 58 which engages a groove in the hub of the pinion 56, so that the latter shifts horizontally with the carriage in letter-space direction. A rock arm 59 (see Fig. 3) is connected by a link 60 to the oscillating arm 41. The hub of the rock arm is provided with a square opening through which the shaft 55 extends, and by rocking the shaft, the arm 41 and typewheel 38 can be shifted to strike against the platen. The carriage is provided with two rearwardly projecting lugs 59' having large openings therein through which the shaft 55 extends and arranged on opposite sides of the hub of the rock arm 59, so that the latter moves in letter-space direction with the carriage. It should be noted that no part of the weight of the typewheel carriage is borne by the typewheel rotating and striker shafts 54 and 55, but is carried entirely upon the guide rods 48 and 52. It should also be noted that a line extending through the main guide rail 48 and the pivot of the striker arm 41 will pass through the printing point at the front of the paper platen, and by reason of this arrangement the striking of the typewheel against the platen will not tend to disturb the alignment of the printed matter.

A collar 61 is mounted on the shaft 40 and is connected to the typewheel spindle by a screw 62 extending through a longitudinal slot in the shaft. A plunger 63 which is longitudinally shiftable in lugs on the oscillating arm 41 is provided with a fork 64 which engages a groove in the collar 61 and is adapted to shift the typewheel to effect the printing either of characters or of the figures and punctuation marks. To compel the rotation of the typewheel with the shaft 40 and still permit its vertical shift, an eccentric member or lug 65 is provided which is fixed to the upper end of the shaft 40 and extends through an eccentric opening in the typewheel.

The plunger 63 is pivoted at a point near the pivotal axis of the striker arm to the upper end of a link 66 which is pivoted at its lower end to the horizontal arm of a bell-crank lever 67. The latter is pivotally mounted on a depending lug of the carriage and carries a roller 68 on its depending arm which is adapted to be engaged by the horizontally extending bail 69, the up-turned ends of which are pivoted to the brackets 49 and 50.

By properly operating the shafts 54 and 55 and the bail 69, the rotating, striking and case shift movements of the typewheel are effected. As in the prior patent referred to, a centering wheel 70 is fixed to the upper end of the shaft 40 and cooperates with an arm 71, the latter being pivoted to the striker arm and being controlled by a cam 72 fixed to the

carriage. Preferably, also, as set forth in the prior patent mentioned, the carriage is provided with a suitable inking roller.

The shaft 54 which, as stated, is geared to the typewheel, is provided at its right-hand end with a pinion 73 which is engaged by a toothed segment 74. The latter is fixed to the right-hand end of an oscillating shaft 75 which is journaled at one end in the right-hand bracket 49 and at its opposite end in a lug 76 on an upright bracket 77. A depending arm 78 of this shaft (see Fig. 3) is connected to the adjacent ends of two springs 79. The rear end of one spring is fixed to the bracket 77 and the forward end of the other spring is connected to an adjusting screw 80. These springs serve to restore and hold the shaft 75 and the typewheel geared thereto in normal central position.

20 A cross-bar 81 fixed to the shaft 75 is arranged to be engaged by two actuating plungers 82 which are guided in the bracket 77 and are connected to the armature yokes of two solenoid plungers 83 that are mounted on 25 and extend rearwardly from the brackets 77. Coil springs 84 on the plungers hold them in engagement with the cross-bar 81. The operation of the solenoids serves to rotate the shaft 75 and parts geared thereto, including 30 the typewheel, either in right or left hand direction.

The apparatus and the extent of rotation of the typewheel are controlled by a selecting mechanism which is adapted to be actuated or 35 controlled in response to signals transmitted over a line circuit. The apparatus and selector mechanism are adapted for use in connection with a five unit code—that is to say, a code in which each character or signal is 40 represented by permutations of five positive and negative impulses or intervals, or of five intervals of current and no current. The selector mechanism is controlled by five selector magnets 1, 2, 3, 4 and 5 mounted on a 45 bracket 85 at the rear right-hand portion of the base plate (see Figs. 8 and 8^b) and are arranged to respond respectively to the corresponding intervals or units of the code. Preferably, as shown, the magnets are compactly 50 arranged upon the bracket 85—3 magnets in an upper row and 2 in a lower row. These magnets control a series of spring actuated latches 86 which are pivotally mounted on a shaft 87 which in turn is mounted on the 55 front face of the bracket 85. The latches control a series of horizontally movable, spring-actuated plungers 88 which are guided in bracket 89 and in plate 90 (see Figs. 7 and 8). The latches (see Fig. 8) engage notches in 60 the rear ends of the plungers 88. Three of the latches are arranged below their respective plungers and two above the same, and springs 91 are provided for pressing the latches toward their respective plungers. The 65 lower row of latches are provided with up-

wardly projecting tail-pieces 92 and the upper row with similar downwardly projecting tail-pieces, and these tail-pieces are arranged to be engaged respectively by a set of actuating rods or plungers 93 which are connected to the cores or armatures of the solenoid selecting magnets 1, 2, 3, 4 and 5, the arrangement being such that whenever one of the magnets is operated, a corresponding latch is shifted against the pressure of its spring and thereby releases the plunger 88 controlled thereby. Springs 94 coiled about the plungers 88 extend between the bracket 89 and the collars 95 on the plunger and tend to shift the plungers forwardly when the latches 86 are tripped. 70 75 80

The plungers 88, corresponding in the present construction to the selector magnets 1, 2, 3 and 5, control the setting or operate a set of four selector plates 96 which control the setting of a series of stop pins 97. The stop pins cooperate with an arm 98 (see Fig. 6) on the shaft 54 to limit the extent of rotation of the shaft and of the typewheel actuated thereby. The stop arm 98 (see Fig. 6) is fixed to the extreme right hand end of the shaft 54 which projects through the bracket 49 and is provided with an outwardly offset upper end portion which is arranged adjacent the selector plates 96. The latter are carried by and arranged to oscillate upon a flanged hub 99 which is fixed to the inner face of a plate 100, spacing washers being interposed between the selector plates. The plate 100 is fixed to two horizontal pins or bolts 101 which project outwardly from the bracket 49, spacing sleeves 102 (see Fig. 10) being interposed between the plate 100 and the bracket. Each selector plate is provided with a slotted ear 103 on one side which engages one of the spacing sleeves 102, and the length of the slots 105 limits the extent of oscillation of the plates. 100 105

The plates are shifted or set in position by a series of levers 104 which are mounted at their lower ends on a series of horizontal shafts 105 that are journaled in a bracket 106 on the base plate. The upper ends of the levers are slotted and engage pins 104' that are fixed respectively to projecting lugs on the lower edges of the selector plates 96. Cross-arms 107 are fixed to the shafts 105 and springs 108 engaging the lower ends of the cross-arms serve to hold these parts and selector plates in the normal position shown. The upper ends of the arms 107 are provided with adjustable abutment screws 109 which are arranged to be engaged respectively by the forward ends of the plungers or trip rods 88 corresponding to the selector magnets 1, 2, 3 and 5. Whenever one of these selector magnets is energized, it will trip its latch and release the corresponding plunger 88. The springs of these plungers are stronger than the springs 108 which hold the selector plates in position and will serve to actuate the rods and plates in different combinations and in 110 115 120 125 130

accordance with the operation of the selector magnets. Selector magnet 4, in the construction shown, does not control a selector plate, but when energized the corresponding plunger engages one of two normally open contact springs 110 and brings the same into engagement. These contacts (see Fig. 8) are mounted upon and depend from a lug that projects upwardly from the plate 90. This plate is mounted on the bracket 106.

10 The selector stop pins 97 are carried by a drum comprising two plates 111 and 112 which are fixed to a central flanged support 113, which is preferably hollow to reduce its weight. The plates are provided at their side edges (see Fig. 9) with ears connected by sleeves 114 and these sleeves slidably engage the horizontal bolts 101. Each of the pins is provided with a coil spring 115 which extends between the outer plate 112 and a collar 116 fixed to the pin and the springs serve to hold the pins in normal position with the collars 116 engaging the plate 111.

15 At each operation of the machine the stop pin drum is shifted to the left by means of a lever 117 which is pivotally mounted adjacent its lower end on the bracket 106 and the upper end of which is arranged to engage an abutment 118 on the hub of the stop pin drum.

20 The lower end of the lever 117 is arranged to be engaged by the horizontal plunger or actuating rod 119 which is guided in a lug on the bracket 106 and is connected to the yoke armature of a double solenoid magnet 120.

25 When the drum actuating magnet 120 is energized, it shifts the pin drum inwardly and brings the stop pins 97 in engagement with the selector plates. The latter, as shown in Figs. 10^a, 10^b, 10^c and 10^d are provided with

30 openings which are variably arranged and such that when the plates are set in accordance with the different code signals, two of the pins are projected through the selector plates and brought into the path of travel of the stop arm 98. One of the other of the typewheel rotator magnets 83 is then operated until the stop arm engages one or the other of the projected pins, which thus serves to arrest the typewheel with the proper character

35 in printing position. Which of the two rotator magnets 83 is operated, is determined by the operation of the selector magnet 4 which either closes the contacts 110 or leaves them open. In one position of the selector

40 plates, no pins will be projected and the shaft 54 and typewheel operated thereby will be rotated in one or the other direction until the stop arm 98 engages a lug 121 formed upon the lower edge of the plate 100 and extending

45 through elongated slots in the selector plates. When the drum actuating mechanism 120 is deenergized, the springs 115 on the stop pins and on two pins 97' return the pin drum and other parts operating the magnet to the normal position shown in the drawings. When

the rotator magnet is deenergized, the centering spring 79 will restore the parts operated thereby, including the typewheel, to normal central position. Preferably additional means are provided for accurately centering 70 the shaft 54 and typewheel geared thereto. This means comprises a cam 122 (see Figs. 6 and 10) mounted on the shaft 54 adjacent the stop arm 98. This cam has high and low semi-circular portions and intermediate 75 shoulders. It cooperates with a pair of oppositely disposed pawls 123 which are pivotally mounted on the outer face of the bracket 59 and have upwardly projecting dogs connected by a spring 124. This spring holds 80 the pawls in normal position in engagement with the shoulders of the cam 122 and with the upwardly projecting portions of the pawls in engagement with two stop pins 125 that project outwardly from the bracket 49. 85 When the typewheel and shaft are shifted in one or the other direction, one or the other of the pawls will be oscillated against the tension of the spring 124 and will react to bring the shaft and typewheel back to the normal position when the extent of movement of the shaft and typewheel is slight. A greater extent of movement will cause the dog to ride on the high semi-circular portion of the cam and it will then have no effect until the shaft and typewheel are nearly back to normal position. This device affords a quick return to the typewheel when its extent of movement is slight. 90

95 Preferably, also, means are provided for locking the typewheel rotating means against movement until after the stop pin drum has been shifted to project the stop pins 97 through the selector plates. For this purpose a pair of locking dogs 126 (see Fig. 5) are pivoted on the inside of the bracket 49 and are arranged to engage shoulders on a part 127 on the shaft 54. A spring 128 connects the locking pawls and holds them in normal position with lugs 129 thereon engaging the inner end of a release lever 130. The latter (see Fig. 6) is in the form of a bell-crank and is pivoted on the outer face of the bracket and one arm extends therethrough and engages the lugs 129 of the locking pawls. The other arm of the bracket depends from its pivot and is arranged to be engaged by a forwardly projecting lug 131 which is mounted on the lower portion of the plate 111 of the stop pin drum. When the latter is actuated 110 to set the stop pins, the lug 131 engages the release lever 130 and shifts the pawls 126 so that the typewheel can be rotated. 115

120 When the selector plates have been set in accordance with any code signal and the drum has been shifted to project the selected pins through openings in the plates, the latter will hold the plates in the particular set position until the stop pin drum is returned to normal position. For this reason the selector actu- 125 130

ating rods or plungers 88 can be reset as soon as the drum magnet 120 operates. The reset mechanism comprises a vertically disposed plate 132 (see Figs. 8 and 8^a) which is pivotally connected between its ends to a pair of lugs 133 on the upper end of the bracket 89. This plate at its lower end carries a bar 134 which has notches in its edge through which the plungers 88 extend and which is arranged to engage the collars 95 fixed to the plungers. A horizontal actuating rod 135 is arranged to engage the upper part of the reset plate 132. This rod is guided in the upper portion of the bracket 89 and is connected to the armature yoke of a double spool solenoid reset magnet 136. When the stop pin drum moves forward a short distance, the circuit of the reset magnet is energized and the latter is actuated to shift the plate 132 and thereby force any of the selector actuating rods which may have been shifted back to normal position in reengagement with the latches 86 and with their actuating springs 94 compressed. Preferably, the resetting bar 134 is held in engagement with the collars 95 by a light spring 137 interposed between the plate 132 and an upwardly projecting lug on the plate 90. The resetting plate 132 carries a contact screw 138 which is arranged to cooperate with a contact spring 139. These contacts are interposed in the operating circuit of the apparatus, or preferably in the circuit of the relay which controls the operating circuit. When any selector magnet is operated and the corresponding plunger or actuating rod 88 shifted, the contacts are engaged, but if none of the selector magnets are energized, the operating circuit will not be closed.

The armature yoke of the reset magnet 136 also carries an adjustable screw 140 which is arranged to engage the longer of two normally open contact springs 141 and close these contacts whenever the reset magnet is actuated. These contacts control the operation of the striker magnet which shifts the typewheel rearwardly against the platen.

The striker magnet 142 is in the form of a double solenoid and is mounted in upright position on the left hand end of the base plate adjacent the bracket 50 (see Fig. 1). Its armature yoke is pivotally connected to the central portion of a horizontal lever 143 (see Fig. 3^a). The latter is pivoted at its forward end to the bracket 50 and at its rear end is connected to the lower end of an adjustable link 144 which in turn is connected at its upper end to a cross arm 145 fixed to the striker shaft 55. When the striker solenoid 142 is energized and its plunger and armature yoke pulled down, the motion transmitted through the horizontal lever 143 and link 144 rotates the striker shaft and causes the typewheel to strike against the platen. Normally the striker mechanism is in the position shown in the drawings, with the for-

ward end of the cross arm 145 in engagement with a stop screw 146 that is adjustably mounted in a lug 146' on the bracket 50. The striker mechanism is returned to and is yieldingly held in normal position by a spring 147 which extends between an adjusting screw 148 and a crank arm 149 on the right-hand end of the striker shaft 55 (see Fig. 1).

A bracket 150 fixed to the base plate in rear of the striker magnet 142 is provided with a rearwardly projecting part carrying a contact screw 151 (see Fig. 3^a). This contact cooperates with an insulated contact 152 which is mounted on the rear end of an arm 153. This arm or lever is pivoted between its ends on the bracket 150 and carries an adjustable abutment screw 154 on its forward end. A spring 155 normally holds the contacts in engagement, but whenever the striker mechanism is actuated the rear end of the arm 145 strikes the abutment screw 154 and opens the contacts to disengage the contacts and open the operating circuit.

The conductor leading to the contacts 152 on the oscillating levers 153 is connected to an insulated clip 156 fixed to the bracket 150 and connected to the rear end of the contact 152 by a coil spring 156' of piano wire (see Fig. 2). The typewheel is shifted step by step between printing operations by a suitable letter-space mechanism comprising fixed and movable rack bars 157 and 158 which are arranged in horizontal position below the main guide or track bar 48 of the carriage. The rack bar 157 is fixed at its ends to the brackets 49 and 50 while the rack bar 158 is slidably mounted at its ends in guides 159. Holding and spacing pawls 160 and 161 (see Figs. 1 and 3) are pivotally mounted on the lower portion of one of the lugs 47 of the carriage, and springs 162 mounted on the other carriage lug 47 engage the pawls and press them into engagement with the fixed and movable racks respectively.

A spacing lever 163 is pivotally mounted adjacent its lower end to lugs 164 on a bracket 165 and its upper end is pivotally connected to the movable rack bar 158. A spring 166 interposed between the bracket 165 and the lower end of the space lever holds the latter and the rack bar 158 in normal position with the lever in engagement with a stop screw 167 which is adjustably mounted on the upper end of the bracket 165. An actuating rod 168 is guided in bracket 165 and is connected to the armature yoke of a double solenoid magnet 169. The latter is fixed to the bracket 165 and projects laterally therefrom. Whenever the printer magnet 142 is energized, the spacer magnet 169 is also energized and shifts the rack bar 158 to the left through the space of one tooth, so that when the magnet is deenergized the spring 166 will shift the lever and the rack and advance the car-

riage and typewheel one step in letter-space direction.

A cord 170 connected to the carriage extends toward the left side of the machine over a guide roller 171 on the upper front portion of the bracket 50 and thence over a spring drum 172 mounted on the outer face of the bracket. This drum tends to draw the carriage back toward the left, but is normally prevented from doing so by the engagement of the spacing and holding dogs with the racks 157 and 158.

As the carriage is advanced to the right, the cord 170 is unwound from the spring drum 172. By disengaging the holding and spacing dogs from the rack bars, the spring drum will act to quickly return the carriage to commence another line of print. To release the dogs, the horizontal bar 173 is arranged between the spacing rack bars and is mounted on two screw bolts 174 which are fixed to the stationary rack bar 157 and extend through inclined slots 175 in the releasing bar. The holding and spacing dogs are provided with depending lugs 176 which engage the upper edge of the releasing dog and the latter is actuated or shifted upwardly and toward the right by a lever 177 which is pivotally mounted on a bracket 178. The latter carries a single spool solenoid magnet 179, the core of which is provided with an actuating rod 180 which is arranged to engage the lever 177 and thereby shift the carriage return bar 173, thereby lifting the holding and spacing dogs 160 and 161. When this occurs, the drum 172, of course, quickly returns the carriage to the lefthand side of the machine.

The carriage return bar 173 is provided with a forwardly projecting lug 189 which, when the bar is shifted, is engaged by a locking pawl 190 pivoted on rack bar 158 to hold the bar in shifted position. A spring 191 extending between the pawl and the rack bar 158 yieldingly holds the latter in engagement with a pin 192. After the return of the carriage, the holding and spacing dogs are still maintained in disengaged position, but as soon as the spacing magnet 169 is energized, the movement of the rack bar and the locking pawl toward the left releases the carriage return bar 173. The holding and spacing dogs then drop into engagement with the racks and are ready to effect the advance of the carriage as soon as the spacer magnet is deenergized.

The letter-spacing magnet 169 is operated upon the printing of each character. The carriage return magnet 179 is operated in response to the transmission of special signals over the line. The spacer magnet may also be so operated to effect the spacing between words. Preferably the lever 177, which operates the carriage return bar, is provided at its right hand end with a forwardly project-

ing finger piece so that, if desired, it may be operated by hand.

The typewheel in normal position effects the printing of the characters in its upper row. It can be shifted vertically, as described, to effect the printing of figures or characters by actuating the shifter bar or bail 69, to thereby raise the typewheel against the tension of a spring 193 which extends between lugs fixed respectively to the arm 41 and the shifting plunger 63. The shift bar or bail 69 is actuated by a lever 194 (see Figs. 2 and 5). This lever is pivotally mounted between its ends on the forward portion of a bracket 195 and is provided at its upper end with an adjustable screw 196 which is arranged to engage and actuate the shifter bar. The bracket 195 also carries the figure and letter shift solenoid magnets 197 and 198, the cores of which magnets are provided with rods or plungers 199 and 200 and which in turn are arranged to operate respectively the lever 194 and a latch 201. The latch 201 is pivotally mounted on a lug on the front side of the bracket 195 and is provided with a spring 202 which normally holds it in engagement with its actuating plunger 200.

When the figure shift shaft 197 is energized, its plunger shifts the lever 194 and thereby, through the shifter bar or bail 69, raises the typewheel until the lower row of figures and punctuation marks is in printing position. This shift of the lever 194 also engages its lower end with the spring actuated latch 200, so that it and the typewheel are held in shifted position. To return the typewheel, the letter shift magnet 198 is energized to release the latch and the spring 193 pulls the typewheel down to its lower position.

The upper end of the bracket 195 carries a contact screw 203 which cooperates with the insulated contact spring 204 on a pivoted arm 205. A lug 206 on this arm is arranged to be engaged by the lever 194 and thereby engage the contacts when the figure shift magnet 197 is actuated and disengage the same when the letter-shift magnet 198 is energized. A conductor leading to the contact 204 is connected to a fixed clip 207 and the latter in turn is connected by a coil spring 208 of piano wire to the contact.

The several functions of the printer, other than printing—such as the line feed, carriage return, letter spacing and figure and letter shift—are controlled by a number of pairs of insulated contacts arranged in a semi-circular series above the stop pin drum of the selector magnet. Each pair of contacts is mounted on a separate support 209 which is connected by a pair of screws 210 to a plate 211 (see Figs. 6 and 8). The plate 211 is mounted upon the rear ends of the screw bolts 101 which project laterally from the bracket 49. In the form shown, the plate 211 is provided

with a pair of outwardly projecting lugs 212 which guide the upper end of the pin drum shift lever 117. Preferably, as shown in Fig. 6, the supports 209 are provided with curved faces which engage the inner face of the plate 211 so that by means of the screws 210 the positions of the supports and contacts carried thereby can be adjusted.

Each pair of contacts comprises an upper 10 spring contact 213 and a lower relatively stiffer and shorter contact 214. The contacts of each pair are normally held disengaged by a lever 215 pivoted to the corresponding support and extending outwardly over the stop 15 pin drum and over the selector plates. These levers are provided at their inner ends with upwardly projecting lugs which engage the spring contacts 213. The lower edges of the levers are provided with lugs which engage 20 the plate 111 of the stop pin drum. These levers also extend through notches in the fixed plate 100 and are arranged to cooperate with notches and lugs 216 and 217 formed upon the selector plates.

In the normal retracted position of the 25 drum, the engagement of the plate 111 with the lugs on the lower edges of the lever 215 hold the latter out of engagement with the selector plates and in position to hold the 30 pairs of contacts 213 and 214 disengaged. As the spring drum moves forwardly, the levers are pressed into engagement with the upper edges of the selector plates. The notches 216 and 217 on the latter are variably arranged 35 so that in different settings of the plates one of the levers can be selected and be depressed sufficiently to permit the engagement of the corresponding pair of contacts. However, the central contact lever is lowered and each 40 pair of contacts engaged at each operation of the drum irrespective of the setting of the selector plates. The other contact levers, however, are selectively controlled by the plates. Of course, the return movement of 45 the drum raises all of the levers and disengages the pairs of contacts controlled thereby.

The operation will be understood from the description already given and from a consideration of the circuits as shown in Fig. 11. 50 The apparatus is controlled by a relay R which acts in response to the two different line conditions of the five-unit code to shift its tongue between the spacing and marking contacts. A distributor brush D, which 55 operates in substantial synchronism with the transmission of the code impulses over the line, successively connects the marking contact of the line relay to a series of contacts 1, 2, 3, 4 and 5 which are connected respectively 60 to the corresponding selector magnets. The tongue of the line relay is connected to battery so that as the different code signals are received the selector magnets will be variably 65 operated at different combinations and will

correspondingly, as described, effect different settings of the selector plates.

The operating circuits of the machine are controlled by a relay 218 and the contacts 138 and 139 are interposed in the circuit of this 70 relay. The distributor brush D, or a suitable switch operated in synchronism with the brush D, is arranged to connect the local battery to the contact 138 after the distributor brush has passed over the selector magnet 75 contacts. As shown in the diagram, the brush D is arranged to engage a segment 6 which is connected to the contact 138, and, since the line circuit signal is preferably such that when the brush engages the contact 6 the tongue of the line relay R will engage its marking contact, the engagement of the brush with contact 6 will connect the contact 138 to the local battery. But the operating pulse 80 relay 218 will not be energized to effect the 85 operation of the printer unless the contacts 138 and 139 are engaged by the previous operation of one or more of the selecting magnets. If, however, one or more of the selector magnets have been operated, such operation will, 90 as described, move the plate 132 and engage the contacts 138 and 139. Then when the brush D or other means connects the contact 138 to battery an operating pulse will pass 95 through the coil of the relay 218 and thereby shift the switch tongue 219 into engagement with its front contact. This contact is connected to a local battery B' through the normally closed unlocking switch 230 and through the normally engaged unlocking 100 switch contacts 151 and 152. The relay tongue 219 is also connected to the coil of this relay so that when the latter is energized a locking circuit is closed through its coil. The relay tongue 219 is also connected to the coil 105 of the drum magnet 120, to the switch tongues 220 and 221 of a relay 222 and to the switch tongues 223 and 224 of a relay 225. The tongue 223 of the relay 225 is normally connected through its back contact to one of the 110 4th pulse contacts 110, the other of which is connected to the coil of the relay 222. Relay tongue 223 is also connected through its back contact to one of the drum switch contacts D S, the other of which is connected to the 115 coil of the reset magnet. By reason of this arrangement, the operating pulse energizes the operating relay and drum magnet and connects the coils thereof to the local battery through the unlocking switches 152 and 220. 120 Also, if the signal has closed the 4th pulse contacts 110, the 4th pulse relay will be energized and locked in by the engagement of the tongue 220 with its front contact. This tongue at the same time will also close the circuit of one or the other of the rotator magnets 83. The latter are relatively slow-acting, as compared with the 4th pulse relay, and the latter will operate in time to determine 125 which of the rotator magnets is energized in 130

accordance as to whether the 4th pulse of the code signal has been a marking or a spacing pulse. It should be noted that the coil of the 4th pulse relay is connected to the local battery B' through the 4th pulse contacts 110 and the switch tongue 223 of the print relay 225. But, if operated, the tongue 220 of the 4th pulse relay will connect its coil directly to the tongue 221 of the operating pulse relay by engaging its front contact.

10 While the operating pulse thus simultaneously energizes the operating pulse relay 218, the drum magnet 120 and one of the rotator magnets 83, the typewheel will not be rotated until the selector drum has completed its forward movement and tripped the locking dogs 126 which, as described, normally hold the typewheel and its operating gearing against movement.

15 The partial forward movement of the selector drum will close the switch contacts D S (which, as stated, are closed at each operation of the selector drum), and thus complete the operating circuit of the reset magnet 136 which, as stated, is connected to the circuit of 20 the operating relay by the switch contacts D S and by the tongue 223 of the print relay 225. The operation of the reset magnet shifts the plate 132, opens the contacts 138 and 139 and, 25 as described, restores any of the plungers 88 of the selector magnets which have been shifted. It also closes the contacts 141 and thereby completes the circuit of the print relay 225. The tongue 224 of this relay is connected to the tongue 219 of the operating pulse relay, and its front contact is connected to the coil of the print relay, so that, when the latter is actuated, this coil is locked in closed condition. The shift of the tongue 223 of the 30 print relay opens the circuit of the reset magnet and the selector magnets and their plungers can then be actuated in accordance with the next succeeding line signal, before the operation of the printer is completed.

35 The shift of the print relay tongue 223 which, as stated, is connected to the circuit of the operating pulse relay, also by engagement with its front contact closes the circuit from the local battery through the switch tongue 226 of a cut-out relay 227 and thence through the striker and letter-space magnets in series. The typewheel is then swung forwardly to print the selected letter and also, by disengaging the unlocking switch contacts 151 and 152, opens the operating circuit of the printer so that all magnets and relays are restored to normal condition to effect the printing of the next signal.

40 When the drum magnet is de-energized the pins 97 are withdrawn from the selector plates 96 so as to release the latter. When this occurs the springs 108 return or tend to return the selector plates to normal. But, if in the meantime, one or more of the latches 45 86 have been tripped by the next signal and

the corresponding controlling members or plungers 88 conditioned for operation or moved to operative position by the springs 94, such conditioning or setting of the controlling members or plungers will be transferred to the selector plates as soon as they are released by the return of the pin drum to normal. This delayed operation is permitted because the selector controlling or setting movements of the plungers 88 are not effected positively but by means of the yielding springs 94.

45 If the particular setting of the selector magnets corresponds to a function such as the line feed, the operating pulse will, as before, energize the relay 218 and the drum magnet 120 and, as the selector drum moves forwardly, the position of the selector plates would permit the engagement of the switch contacts L F and the circuit will be completed from the tongue 221 of the relay 222 through its back contact and one of the windings of the cut-out relay 227 to the switch contacts L F and thence to the line feed magnet 31. The latter will then be energized to effect the operation of the line feed mechanism. Since this circuit passed through the coil of the cut-out relay, it will operate its switch tongue 226 and also a switch tongue 228 which would then serve to close the circuit from the battery B' through the coil of an unlocking relay 229. The latter would open the switch 50 230 and restore the parts of the printer to normal. When the line feed is thus actuated, the reset magnet 136 will operate, as previously described, and close the circuit of the print relay 225, but since the cut-out relay has been energized and opened the normally closed switch tongue 226, the operation of the print relay will not close the circuit of the 55 striker and letter-space magnets and the latter will not be operated.

60 If, for example, the function selected had been the carriage return, the operation would have been similar, except that, with the arrangement shown, the 4th pulse of the carriage return signal is a marking pulse and, hence, contacts 110 would be closed and the 4th pulse relay 222 energized. Hence, the circuit from the relay tongue 221 would be completed through its front contact to a second winding of the cut-out relay 227 and thence, through the switch contacts C R, to the carriage return magnet 179. It is noted that the function contacts control and are connected in parallel in the circuit of one or the other of the coils of the cutout relay and the latter is operated whenever a pair of function contacts is selected.

65 The operations effected occur in the following order: (1) The selector magnets are operated to set the plates and close the contacts 138 and 139. (2) The operating pulse relay is actuated, locks itself in, and connects the contacts 110 to the local battery; if these

contacts have been engaged the 4th pulse relay 222 is also operated. (3) The operation of the drum magnet occurs shortly after the operation of the relays 218 and 222. Although the drum magnet receives current at the same time as the relays, the latter act more quickly. (4) As soon as the selector drum moves a short distance, the drum switch D S is closed and effects the operation of the reset magnet 136. (5) As soon as the selector drum completes its movement, it unlocks the rotator mechanism, and one of the rotator magnets, which has been receiving current through the tongue 220 of the 4th pulse relay, rotates the type-wheel. (6) As soon as the reset magnet completes its travel, it connects the print relay to the local battery, as described, and the operation of the latter disconnects the 4th pulse contacts 110 and the reset magnet from battery and connects battery to the striker and spacer magnets in series. (7) When the typewheel strikes the platen, the arm 145 opens the unlocking switch 152 and all operated relays and magnets are restored to normal. When one of the function magnets is actuated, the succession of operations is the same, except that the partial forward movement of the selector drum will engage the selected function switch contacts and connect battery through one winding of the cut-out relay and the coil of the corresponding function magnet. The operation of the cut-out relay, as described, prevents the operation of the striker and letter-space magnets, as described, and connects battery to the unlocking or restoring relay 229.

From the foregoing it is obvious that the operating pulse relay must be actuated in order to initiate the operation of the printer and it will not be so actuated unless one of the selector magnets has been operated to close the contacts 138 and 139. The 4th pulse relay 222, through its tongue 220, determines the direction of rotation of the typewheel and through its tongue 221 determines which of two sets of function switch contacts will be connected to battery, since one set of the function switch contacts is connected to the front contact of the relay tongue 221 and another set to the back contact of this tongue. The particular circuit closed is of course determined by the setting of selector plates which, as noted, are arranged to select one of the pairs of function switch contacts when a function signal is received. It should be noted that the operation of selecting magnet 4 does not immediately effect the operation of the 4th pulse relay, but merely closes the contacts 110 which, when the operating pulse relay 218 is energized, completes the circuit of the 4th pulse relay. Since this circuit passes through the print relay tongue 223 and its back contact, the 4th pulse relay 222 can only operate

before the print relay 225 operates. This prevents the operation of the 4th pulse relay during the printing of a letter.

Both the operated pulse relay and the 4th pulse relay are provided with two windings. In the case of the latter, the relay is operated through one winding and locks itself in with a weaker current through a second winding. The operating pulse relay is operated through one winding and locks itself in with a weaker current through both windings in series.

The function switch contacts S are connected to the contact screw 205 which operates with the contact 204 and the latter is connected to the circuit of a signal bell 231. The lower row of figures and punctuation marks on the typewheel has a blank space in line with some one of the characters—for example, the letter "J"—and the signal for this character is designed to select the switch contacts S. But to complete the circuit of the signal magnet, it is also necessary to close the contacts 204 and 205 by effecting the operation of the figure shift magnet 197. But the circuit of the signal 230 can be closed by transmitting the figure signal, followed by the signal for the letter "J". This circuit will be opened by operating the letter shift magnet 198.

A lamp 231 is connected to a series of contacts arranged between the selector magnet contacts of the distributor. When signals are being received, some of the impulses or intervals are necessarily marking and, as the distributor brush passes over the contacts connected to the lamp, the latter will receive current and flash when marking intervals or impulses are received. When no marking intervals or impulses are sent over the line, the lamp will not be affected. This arrangement prevents the loss of messages since, when the lamp flashes, the printer should operate, and, unless this is the case, attention is directed to the fact that the printer is not properly operating.

The five controlling relays (see Figs. 2 and 3) are mounted in the upper portion of a supplemental frame 233 which is arranged in the rear central portion of the main frame. This supplemental frame has a triangular base 234 which is fixed to the upper ends of three screws 235. The latter extend through openings in the base plate and are provided with headed lower ends. Springs 236 are coiled about the screws and are interposed between the base plate 10 and the base 234 of the supplemental frame and also between the base plate and the heads of the screws. In this way the controlling relays are yieldingly supported and the vibration imparted to the main frame by the operation of the printer will be absorbed by the springs and will not tend to improperly effect the contacts of the controlling relays.

Obviously, changes may be made in the details set forth without departure from the essentials of the invention as defined in the claims.

We claim as our invention:—

5. In a telegraph printer, a set of selectors, printing means controlled thereby, a set of selector shifters, individual springs for effecting the selector setting movements of said shifters, latches for holding said shifters in retracted positions, a set of selecting magnets for tripping said latches, and means for resetting said shifters independently of said selectors and in advance of the complete operation of said printing means. 10

15. 2. In a telegraph printer, a type wheel, a rotator therefor, a co-operating striker, selecting pins for arresting the rotation of said type wheel, a set of selector plates controlling said pins, actuating shifters for said plates having a one-way connection therewith, a resetting member for said shifters, and means for operating the selector pins, resetting member, type wheel, rotator and striker in the order named. 20

25. 3. In a telegraph printer, a type wheel, a rotator therefor, a co-operating striker, selecting pins for arresting the rotation of said type wheel, a set of selector plates controlling said pins, actuating shifters for said plates having a one-way connection therewith, a resetting member for said shifters, a set of selector magnets controlling said shifters, and separate actuating magnets and controlling means for effecting the operation of said pins, resetting member, rotator and striker in the order named. 30

35. 4. In a telegraph printer, a type wheel, a rotator therefor, a co-operating striker, selecting pins for arresting the rotation of said type wheel, a set of selector plates controlling said pins, actuating shifters for said plates having a one-way connection therewith, a resetting member for said shifters, latches for holding said shifters in normal position, means for variably operating said latches in different combinations in accordance with the signals received, and means for successively operating said pins, resetting member, rotator and striker. 40

45. 5. In a telegraph printer, a type wheel, a rotator therefor, a co-operating striker, selecting pins for arresting the rotation of said type wheel, a set of selector plates controlling said pins, actuating shifters for said plates having a one-way connection therewith, a resetting member for said shifters, latches for holding said shifters in normal position, a set of selecting magnets for tripping said latches, and an operating circuit and separate magnets for actuating said pins, resetting member, rotator and striker in order. 50

55. 6. In a telegraph printer, printing means including a set of type and a striker magnet, selecting pins for determining the operation 60

65. magnets for tripping said latches, a reset magnet for restoring said shifters independently of said plates, and an operating circuit and contact means for actuating the selecting magnets, pin magnet, reset magnet and striker magnet in the order named. 75

7. In a telegraph printer, printing means including a set of type and a striker magnet, selecting pins for determining the operation of said printing means, a set of selector plates controlling said pins, a magnet for engaging said pins with said plates, spring-actuated shifters for said plates, latches for holding said shifters in normal position, selecting magnets for tripping said latches, a reset magnet for restoring said shifters independently of said plates, a print relay actuated by said reset magnet, controlling said striker magnet and arranged, when actuated, to restore said reset magnet, and means for operating said selecting pin and reset magnets in order. 80

8. In a telegraph printer, printing means including a set of type and a striker magnet, selecting pins for determining the operation of said printing means, a set of selector plates spring-held in normal position for determining the setting of said pins, a set of shifters having a one-way connection with said plates and spring actuated to set the same, a set of spring-held latches for holding said shifters in normal position, means for tripping said latches in different combinations and for initiating the operation of said printing means, and means for resetting said shifters in advance of the complete operation of said printing means. 85

9. In a telegraph printer, a set of type and a cooperating striker magnet, selector mechanism comprising selector plates and pins and a magnet for engaging the same, actuating shifters for said plates, selecting magnets controlling the operation of said shifters, a reset magnet therefor controlled by said pin magnet, an operating pulse magnet having a locking circuit for controlling said pin magnet, and a print relay actuated by said reset magnet controlling said striker magnet and arranged when actuated to restore said reset magnet, said striker magnet being arranged to open said locking circuit. 90

10. In a telegraph printer, a distributor switch, a set of selecting magnets controlled thereby, contacts controlled by one of said magnets, a set of selector plates controlled by the other selecting magnets, printing means having characters selected in pairs by said selecting plates, an operating pulse relay controlled by said distributor, a relay controlled by the combined operation of said 95

100

105

110

115

120

- contacts and said operating pulse relay, and means controlled by said relays for printing one of the two selected characters.
11. In a telegraph printer, a distributor switch, a set of selecting magnets controlled thereby, contacts controlled by one of said magnets, a set of selector plates controlled by the other selecting magnets, printing means having characters selected in pairs by said selecting plates, an operating circuit controlled by the combined operation of said distributor and said selecting magnets, a locking relay for said operating circuit, a relay controlled by said locking relay and said contacts, and means controlled by said circuit and relay for printing one of the two selected characters.
12. In a telegraph printer, a distributor switch, a set of selecting magnets controlled thereby, contacts controlled by one of said magnets, a set of selector plates controlled by the other selecting magnets, a type wheel yeldingly held in central position, rotators for turning said wheel in opposite directions, stop pins for said wheel adapted to be selected in pairs by said plates, an operating circuit controlled by said distributor, a relay in said circuit controlled by said contacts and controlling said type wheel rotator means, and a striker magnet in said circuit.
13. In a telegraph printer, a distributor, selecting magnets controlled by said distributor, selector plates operated by said magnets, a type wheel, rotating means therefor, stop pins controlled by said plates for arresting said type wheel, a lock for said rotating means, a shifter for engaging said stop pins and said selector plates arranged to release said lock, magnets for respectively operating said rotating means and said shifter, and means controlled by said distributor for simultaneously energizing said operating magnets.
14. In a telegraph printer, printing and function mechanisms, operating magnets therefor, a set of function contacts spring-pressed towards each other, shifters normally holding said function contacts open, a set of character selecting pins, selector plates arranged to be operated in different combinations, and means for engaging said pins and shifters with said plates.
15. In a telegraph printer, printing and function mechanisms, operating magnets therefor including a striker magnet, a cut-out relay for said striker magnet, contacts controlling said function magnets and said cut-out relay, character selecting pins, a set of selector plates adapted to operate in different combinations and selectively control said pins and contacts, an operating circuit having a locking relay, an unlocking relay controlled by said cut-out relay, and unlocking switches controlled respectively by said striker magnet and said unlocking relay.
16. In a telegraph printer, a platen, a sliding carriage therefor, a striker arm pivoted on said carriage, a type wheel journaled on said arm, a main track bar for said carriage parallel with said platen and arranged in a plane extending through the printing point of said platen and the pivot of said striker arm, type wheel rotating and striker operating means, and selecting mechanism controlling the operation of said type wheel.
17. In a telegraph printer, a carriage movable in letter space direction, restoring means for said carriage, fixed and movable letter spacing racks, holding and spacing dogs on said carriage engaging said racks, a spacing magnet for shifting said movable rack, a releasing member for disengaging said dogs, and locking parts for said release bar mounted thereon and on said movable rack and arranged to be disengaged by the operation of said rack.
18. In a telegraph printer, a main frame, a sliding carriage, a type wheel mounted thereon, letter spacing mechanism for said carriage, a type wheel rotating shaft journaled on the main frame and geared to said type wheel, the latter having a number of rows of type, a shifter on said carriage for raising and lowering said type wheel, an actuating bail for said shifter pivoted on the main frame, an actuator for said bail, a locking dog for said actuator, and separate magnets controlled by the line circuit for operating said actuator and releasing said dog.
19. In a telegraph printer, printing and function mechanisms, operating magnets therefor including a striker magnet, a cutout for said striker magnet, contacts controlling said function magnets and said cutout, character selecting members, a set of selector plates adapted to be operated in different combinations to selectively control said members and said contacts, an operating circuit for said magnets having locking means, and means controlled by said striker magnet and said cutout for opening said operating circuit.
20. In a printing telegraph receiver, the combination with printing and letter-spacing devices, of auxiliary function mechanisms, a plurality of devices for selectively controlling said mechanisms, contacts controlled by said selecting devices, and a circuit for the control of said printing and letter-spacing devices and in which said contacts are connected in parallel.
21. In a telegraph printer, the combination with a set of type and striker letter-space mechanisms therefor of auxiliary function mechanisms, a set of selectors operable in different combination for controlling said type, contacts controlled by said selectors for determining the operation of said function mechanisms, and a circuit for disabling said

- striker letter-space mechanisms and in which said contacts are connected in parallel.
22. In a telegraph receiver, recording mechanism, selectable controlling members therefor, one for each character, a set of selectors adapted to be positioned in different combinations to select said members, individual shifters for said selectors, a rotary distributor member and electromagnetic means cooperating therewith to control said shifters, and spring means for effecting the selector setting movements of said shifters and permitting the delayed operation thereof. 70
- 10 23. In a telegraph receiver, recording mechanism, selectable controlling members therefor, one for each character, a set of permutation selectors having openings adapted to be aligned to select said members, individual shifters, one for positioning each of said selectors, a rotary distributor member and cooperating electromagnetic means for conditioning said selector shifters in different combinations, and individual springs for effecting the selector positioning movements of said shifters and permitting the delayed operation thereof, the selected controlling member serving to hold said selectors in set position independently of said shifters. 80
- 20 24. In a telegraph receiver, the combination with a main frame, of printing mechanism movable horizontally thereon in letter-space direction and vertically movable to different case positions, a case shift bail mounted on the main frame for raising and lowering said printing mechanism, an actuator for lifting said bail, a locking dog for holding said bail in raised position, a set of selectors operable in different combinations for controlling said printing mechanism and separate devices responsive to different operations of said set of selectors for respectively operating said actuator and releasing said dog. 90
- 30 25. In a telegraph printer, printing and function mechanisms, operating magnets therefor, a set of selector plates operable in different combinations for selectively controlling the operation of said printing and function mechanisms, shifters for positioning said selector plates, selecting magnets controlling the operation of said shifters, an energizing circuit for said operating magnets having a locking relay, distributor means for controlling the circuits of said selector magnets and said operating circuit in order, means controlled by said operating circuit for resetting said shifters and subsequently restoring said selector plates, normally open contacts in said operating circuit and an actuator adapted to be shifted by the armature of any one of said selecting magnets for engaging said contacts. 100
- 40 26. In a telegraph receiver, recording mechanism, selectable controlling members therefor, one for each character, a set of selectors adapted to be positioned in different combinations to select said members, individual shifters for said selectors, a rotary distributor member and electromagnetic means cooperating therewith to control said shifters, and spring means for effecting the selector setting movements of said shifters and permitting the delayed operation thereof. 110
- 50 27. In a telegraph receiver, recording mechanism, selectable controlling members therefor, one for each character, a set of permutation selectors having openings adapted to be aligned to select said members, individual shifters, one for positioning each of said selectors, a rotary distributor member and cooperating electromagnetic means for conditioning said selector shifters in different combinations, and individual springs for effecting the selector positioning movements of said shifters and permitting the delayed operation thereof, the selected controlling member serving to hold said selectors in set position independently of said shifters. 120
- 60 28. In a telegraph receiver, recording means, a set of permutation members for controlling the same, springs for shifting said members in one direction, individual spring actuated controlling members opposing said springs and cooperating therewith to set said permutation members each in either one of two positions, latches for holding said controlling members in retracted position, a distributor, and electromagnetic means cooperating therewith for tripping said latches in different combinations in response to received signals. 130
- 70 29. In a telegraph receiver, recording means, a set of controlling permutation members each spring-pressed toward one of two positions, individual controlling members spring-pressed to operative position and each serving in such position to set the associated permutation member in the other of its two positions, latches for holding said controlling members in operative position, means responsive to received signals for conditioning said controlling members in different combinations, and means independent of said controlling members for locking and releasing said permutation members. 140
- 80 30. In a telegraph printer, the combination with printing means including a set of type, cooperating striking and spacing mechanisms and auxiliary function mechanisms, of selectable devices individual to the type and function mechanisms, a set of selector plates having openings adapted to be aligned to select said devices, a corresponding set of shifters spring-actuated to move said selectors and thereby position the same in different combinations, latches for holding said shifters in retracted position, a rotary distributor and a cooperating set of electro-mag- 150

- nets for tripping said latches in different combinations, means controlled by said distributor for operating said striker and spacer mechanisms and for restoring said shifters in advance of the complete operation of the printing means, and a cut out for a portion of said operating means controlled by the selectable devices individual to said function mechanisms.
31. In a telegraph printer, the combination with a printing mechanism including a set of type and striker mechanism therefor, of selectable devices individual to the type, a set of selector plates having openings adapted to be aligned to select said devices, corresponding sets of selector shifters and springs cooperating to move and thereby position said selectors in different combinations, individual springs for effecting the selector positioning movements of said shifters, latches for normally holding said shifters retracted, a rotary distributor and a cooperating set of electro-magnets for tripping said latches in different combinations in response to the received signals and operating means controlled by said distributor including means for resetting said shifters in advance of the complete operation of the printing means.
32. In a telegraph receiver responsive to definite interval code signals, a printing mechanism including a plurality of selectable devices, one for each character, a set of permutation members adapted to be positioned in different combinations to select said devices, a corresponding set of shifters each independently movable to position the associated permutation member, and a distributor and cooperating electromagnetic means for selectively conditioning said shifters in different combinations, and individual springs for retaining said shifters in selective condition and for effecting and permitting the delayed operation of the shifters on said permutation members.
33. In a telegraph receiver responsive to definite interval code signals, a printing mechanism including a plurality of selectable controlling devices one for each character, a set of permutation selectors operable in different combinations and having openings adapted to be aligned to receive and select said controlling devices, a corresponding set of shifters, springs individual to said shifters, each shifter and its spring being independently operable to position one of said permutation selectors, and a distributor and cooperating electromagnetic means for selectively conditioning said shifters in different combinations in response to received signals.
34. In a telegraph receiver responsive to definite interval code signals, printing mechanism including a plurality of selectable controlling devices, one for each character, a set of permutation members operable in different combinations for mechanically determining the selection of said controlling devices in pairs, a set of shifters, certain of said shifters being arranged to mechanically position said set of permutation members, means controlled by other of said shifters for rendering one of the selected pair of controlling devices effective, and a distributor and cooperating electromagnetic means for conditioning the set of shifters in different combinations in response to the received signals.
35. In a telegraph printer, a plurality of selector plates, printing means controlled thereby, a stationary platen, a slideable carriage for supporting said printing means, a plurality of operating means for said plates variably operated in accordance with received combinations of impulse conditions, latching means for holding said operating means in position and means for reoperating said operating means independently of said selector plates and in advance of the complete operation of said printing means.
36. In a telegraph printer, a typewheel, a rotator therefor, a cooperating striker, a slideable carriage therefor, selecting pins for selectively arresting the rotation of said typewheel, a plurality of selector plates for selectively controlling said pins in accordance with received code combinations of impulse conditions, actuating shifters for said plates, means for latching said shifters in position, means following the selective operation of said pins for rotating said typewheel to a predetermined stop position, means for thereafter operating said striker and means whereby said actuating shifters may be reoperated before said typewheel is operated by said striker.
37. In a telegraph receiver responsive to definite interval code signals, a printing mechanism including a plurality of selectable controlling devices one for each character, a set of permutation selectors operable in different combinations and having openings adapted to be aligned to receive and select said controlling devices, a corresponding set of shifters for said permutation selectors, means for maintaining said shifters in position, each of said shifters being independently operable to position one of said selectors and means for selectively conditioning said shifters in different combinations in response to received signals.
38. In a telegraph printer, in combination with printing means including a set of types, a cooperating striker and spacing mechanism and auxiliary function mechanism, of selectable devices individual to the type and function mechanism, a plurality of selector disc plates having openings adapted to be aligned to select said devices in accordance with received code combinations of impulses, a cor-

responding set of shifters for operating said selectors in accordance with said received code combinations of positions, latching devices for holding said shifters in operated position and means for operating said striker and spacing mechanism, said operating means being controlled by said selectable devices individual to said function mechanism.

39. In a telegraph printer in combination with a set of type and striker mechanism and a movable carriage therefor of auxiliary function mechanism, a set of selectors operable for controlling said type, further means controlled by said selector switches for determining the operation of said function mechanism, shifter means for variably operating said selectors and means for maintaining said shifter means in locked position.

40. In a telegraph printer, printing and function mechanism, a set of selector plates operable in different combinations for selectively controlling the operation of said printing and said function mechanism, shifters for positioning said selector plates in accordance with received code combinations of impulses, means for locking said shifters in operated position, means controlled by said selector plates for variably operating said printer and further means controlled by said selectors for variably operating said function mechanism.

41. In a telegraph printer, a type wheel, a rotor therefor, a cooperating striker, selecting pins for arresting the rotation of said typewheel, a set of selector plates controlling said pins, actuating shifters for said plates, means for variably operating said shifters in accordance with received code combinations of impulse conditions for variably operating said selector plates, a slidable carriage on which said typewheel is mounted and letter spacing mechanism for said carriage.

42. In a telegraph printer, a typewheel, a rotator therefor, a cooperating striker, selecting pins for arresting the rotation of said typewheel, a set of selector plates for controlling said pins, actuating shifters for said plates, means for variably operating said shifters in accordance with received code combinations of impulse conditions for variably operating said selector plates, a carriage movable in letter space direction for carrying said typewheel, restoring means for said carriage, fixed and movable letter spacing racks, and spacing means for shifting said movable racks.

43. In a telegraph printer, a typewheel, a rotator therefor, a cooperating striker, selecting pins for arresting the rotation of said typewheel, a set of selector plates for controlling said pins, actuating shifters for said plates, means for variably operating said shifters in accordance with received code combinations of impulse conditions for variably operating said selector plates, a platen,

a slidable carriage therefor, a striker arm pivoted on said carriage, said typewheel being journaled in said arm, a main platen bar for said carriage parallel with said platen and typewheel rotating and striker operating mechanism controlling the operation of said typewheel.

44. In a telegraph printer, a typewheel, a rotator therefor, a cooperating striker, selecting pins for arresting the rotation of said typewheel, a set of selector plates for controlling said pins, actuating shifters for said plates, means for variably operating said shifters in accordance with received code combinations of impulse conditions for variably operating said selector plates, a platen, a slidable carriage therefor, a striker arm pivoted on said carriage, a main platen bar for said carriage parallel with said platen, and typewheel rotating and striker operating mechanism controlling the operation of said typewheel.

45. In a telegraph printer, a main frame, a sliding carriage, a typewheel mounted thereon having a number of rows of type, letter spacing mechanism for said carriage, a typewheel, means for rotating the shaft journaled on the main frame and geared to said typewheel, selector disc mechanism, means operating said disc in accordance with received code combinations of impulses, means controlled by said discs for variably operating said typewheel and means for operating said typewheel along with said carriage for letter spacing following each printing of a character.

46. In a telegraph receiver responsive to definite interval code signals, a typewheel mechanism including a plurality of selectable controlling devices one for each character, a set of permutation selectors operable in different combinations and having openings adapted to be aligned to receive and select said controlling devices, a corresponding set of shifters for said permutation selectors, means for maintaining said shifters in position, each of said shifters being independently operable to position one of said selectors, means for selectively conditioning said shifters in different combinations in response to received signals, a carriage movable in letter space direction for carrying said typewheel and restoring means for said carriage.

47. In a telegraph receiver responsive to definite interval code signals, a typewheel mechanism including a plurality of selectable controlling devices one for each character, a set of permutation selectors operable in different combinations and having openings adapted to be aligned to receive and select said controlling devices, a corresponding set of shifters for said permutation selectors, means for maintaining said shifters in position, each of said shifters being independently operable to position one of said selectors, means for

selectively conditioning said shifters in different combinations in response to received signals, a carriage movable in letter space direction for carrying said typewheel, restoring means for said carriage, fixed and movable letter spacing racks and spacing means for shifting said movable racks.

48. In a telegraph printer in combination with a typewheel and striker mechanism therefor of auxiliary function mechanism a set of selectors operable for controlling said type, further means controlled by said set of selectors for determining the operation of said function mechanism, shifter means for variably operating said selectors and means for maintaining said shifter means in locked position, a carriage movable in letter space direction for carrying said typewheel and restoring means for said typewheel.

49. In a telegraph receiver responsive to definite interval code signals, a typewheel mechanism including a plurality of selectable controlling devices one for each character, a set of permutation selectors operable in different combinations and having openings adapted to be aligned to receive and select said controlling devices, a corresponding set of shifters for said permutation selectors, means for maintaining said shifters in position, each of said shifters being independently operable to position one of said selectors, means for selectively conditioning said shifters in different combinations in response to received signals, a slidable carriage on which said typewheel is mounted and letter spacing mechanism for said carriage.

50. In a telegraph receiver responsive to definite interval code signals, a typewheel mechanism including a plurality of selectable controlling devices one for each character, a set of permutation selectors operable in different combinations and having openings adapted to be aligned to receive and select said controlling devices, a corresponding set of shifters for each permutation selector, means for maintaining said shifters in position, each of said shifters being independently operable to position one of said selectors, means for selectively conditioning said shifters in different combinations in response to received signals, a slidable carriage on which said typewheel is mounted, letter spacing mechanism for said carriage, and restoring means for said typewheel.
